(57) **CLAIM**

The ornamental design for a personal vibrator, as shown and described.

DESCRIPTION

FIG. 1 is a perspective view of the personal vibrator showing my new design.

FIG. 2 is a front view of the personal vibrator of FIG. 1.

FIG. 3 is a rear view of the personal vibrator of FIG. 1.

FIG. 4 is a left side view of the personal vibrator of FIG. 1.

FIG. 5 is a right side view of the personal vibrator of FIG. 1.

FIG. 6 is a bottom view of the personal vibrator of FIG. 1; and,

FIG. 7 is a top view of the personal vibrator of FIG. 1.

1 Claim, 5 Drawing Sheets
